INTERMITTENT TEMPLE THREAD CUTTER

James E. Repass, Hopedale, Mass., assignor to
Draper Corporation, Hopedale, Mass., a corpora-
tion of Maine

Application September 7, 1942, Serial No. 457,590

7 Claims. (Cl. 139—266)

This invention relates to a temple thread cutter for a filling replenishing loom, and more particularly to a means for producing controlled intermittent operation in such a device.

Temple thread cutters are employed on filling replenishing looms to trim, at the selvage, the filling ends formed in conjunction with the filling replenishing operation. The temple thread cutters in common use are principally of the continuously operated type, although various forms have been proposed which will operate intermittently. Such prior devices have not proven commercially successful nor practically acceptable because they were too expensive to construct or not dependable in operation.

It is an object of this invention to provide an intermittently operated temple thread cutter which will be simple in construction and compact in form, and which can be adapted to modify existing types of continuously operated temple thread cutters to convert them to intermittently operated devices.

It is a further object of this invention to provide a self contained selvage trimming device which will comprise a means actuated by the presence of a filling end to make the cutter blade operative, and in which the cutter blade will be restrained in a stationary position when no filling end is present.

These and other objects of the invention may be accomplished by the construction illustrated in the accompanying drawings, which are presented as a preferred embodiment of my invention, although it will be understood that I do not wish to be limited, although it will be understood that I do not wish to be limited to the specific structural details, disclosed therein, but wish to be free to use all mechanical equivalents thereof within the scope of the appended claims, and in which:

Fig. 1 represents a plan view of a portion of the magazine side of a filling replenishing loom of conventional design and shows a temple thread cutter embodying the features of my invention in place thereon.

Fig. 2 represents an elevational view in perspective of the temple thread cutter embodying my invention, and shows the disposition of the parts when held in an inoperative position.

Fig. 3 represents the same view of the temple thread cutter as shown in Fig. 2, but shows the parts released from the inoperative position.

Fig. 4 represents an elevational view of the temple thread cutter approximately as seen from the direction 4—4 of Fig. 1.

Fig. 5 represents an elevational view of the side of the temple thread cutter, as seen from the direction 5—5 of Fig. 1, with the parts restrained in an inoperative position.

Fig. 6 represents a detail of a portion of the temple thread cutter, and will be described more fully in the following specifications.

The fragmentary portions of the loom shown comprise a breast beam 1 to which is affixed a magazine 2 for reserve filling carriers. A lay 3 is constructed to reciprocate toward and away from the breast beam. On the lay is secured a shuttle box 4 in a position to trap a shuttle 5 and place it under the magazine, when the lay reciprocates forwardly, to receive a replenished filling carrier as needed. Subsequently, the lay reciprocates rearwardly and the shuttle is picked through the shed of warp threads, W.

When it becomes necessary to replenish the filling carrier presently in the shuttle, a feeler mechanism initiates operation of the transferring mechanism 6 to perform the transfer. Before this is accomplished a thread parter 7 is made to approach the shuttle to part and clamp the filling end F—1 from the outgoing filling carrier and draw it forwardly of the loom.

When the transfer has been perfected and the shuttle is travelling on the first pick thereafter, a second filling end F—2 is formed leading from the thread holder on the magazine to the selvage S. On subsequent picks the filling thread F—3 is distributed through the shed and beaten into the fell.

A temple assembly, generally indicated at 8, is secured in a position adjacent the selvage to hold the woven fabric in extended position. A thread cutter may be combined with the temple to sever the filling ends F—1 and F—2 at the selvage so they may be cleared from the loom.

All of the foregoing procedure is well known in the weaving art and hence an extended explanation of the process is not thought to be necessary here.

Affixed to a stationary part of the loom and in a position to clear the top of the lay and the inner end of the front box plate 9 is a thread holder 10. When the filling ends F—1 and F—2 are formed they will lie across the path taken by the box plate as it reciprocates with the lay. As the lay approaches the front of the loom, horn-like projections 11 and 12 formed on the box plate will engage the filling ends and carry them forwardly also. The filling ends will thus both be brought into contact with the thread holder 10 which will hold them in a forward position.

In this position the filling ends will be brought to bear against the rearmost face of the temple thread cutter and held within the range of action of the cutting mechanism.

The temple assembly comprises a temple bar 13 to the rearmost end of which is attached the temple head 14, containing the usual temple roll arrangement 15 and a support 16 for the temple thread cutter. Attached to, and extending below the temple, approximately at the point of junction of the temple bar and the temple head, is a flange 17 which is positioned to lie across the path of the lay as it approaches its most forwardly position.

The temple bar is resiliently supported on the breast beam of the loom for reciprocal movement forwardly and rearwardly relative thereto in a manner not shown herein but well known in the art. The lay engages the flange 17 on a forward beat and moves the temple assembly forwardly as a unit against a compression spring not shown, connected to the temple bar. The spring returns the temple to its original position when the lay beats back.

There is a passage 18 formed in the support 16 to accommodate the cutter blade 19 for sliding and rocking movement. The cutter blade is of usual form at its rearward end having a nose of somewhat L shaped formation on one side of which, and facing forwardly, is a cutting edge 20. A ledger blade 21 is secured to the adjacent side of the passage 18. The cutting edge 20 and the ledger blade 21 cooperate to perform the cutting operation on the filling ends.

On the opposite side of the passage 16 is placed a plate 22 which bears against the side of the cutter blade. The pressure of the plate 22 on the blade can be adjusted by means of a screw 23 to control the pressure between the cutting edge 20 and the ledger blade. The friction produced by this adjustment acts to retard the free motion of the cutter blade in the passage 18.

The forward end of the cutter blade is constructed with a depending heel portion 24 projecting into the path of the lay.

A pin 25 projects from the temple bar at a point approximately in vertical alignment with the heel of the cutter blade, and it is co-extensive with the lateral direction of the support 16. The pin serves as a support for a spring 26.

The construction as described thus far was known to the prior art, as exemplified by the patents to Stimpson Number 1,366,034, dated January 18, 1921, and Number 1,838,583, dated December 29, 1931, in which form it has had wide commercial use. In such prior devices, the spring 26 mounted on the pin 25 was connected to an integral part of the cutter blade to produce continuous operation thereof while the loom was functioning.

The instant invention discloses a thread cutting device which will have intermittent operation, and in which the parts are so formed that they can be applied to prior devices of the types disclosed in the cited patents to convert them to intermittently operated temple thread cutters, without changing the basic structural parts of the temple assembly.

Instead of actuating the cutter blade directly by the spring 26, the latter is connected to a bell crank lever 27 which is pivotally mounted for rotary movement on the pin 25 as follows:

One arm 28 of the lever extends downwardly across the path of the lay, in a position approximately parallel to the heel 24 of the cutter blade.

A pin 29 is secured to the arm in a position to extend toward the heel 24, and the latter has a flange 30 formed on it against which the pin may abut under certain conditions, in a manner to be explained subsequently.

The spring 26 has a helically coiled portion 31 embracing the pin 25, and another helically coiled portion 32 embracing the pin 29, and it has an end 33 resting in a support 34 on the temple bar. The bell crank lever is formed with a hole 35 large enough to pass over the coils 31, which act as a bearing for it. Other spiral coils 36 of the spring serve as a retainer to keep the bell crank lever in position on the pin 25.

This form of spring is shown in Patent No. 1,693,942 to Stimpson, dated December 4, 1928, and is also used in the aforementioned Patent No. 1,838,583. It may be adapted, without modification, to the present device.

The spring is mounted so that it will act on the pin 29 to rotate the bell crank lever in a counterclockwise direction, that is, it will move the arm 28 toward the rear of the loom.

The pin 29 is placed on the forwardly side of the flange 30, and when the bell crank lever is rotated as described above, the pin will contact the flange and cause the cutter blade to be moved rearwardly. When this occurs the cutting edge 20 will be projected beyond the rearmost face of the support 16 and into a position where it can engage both the filling ends F-1 and F-2.

In this position the arm 28 of the lever and the heel 24 of the cutter blade will extend rearwardly beyond the flange 17. Thus, when the lay reciprocates toward its most forward position it will first contact the parts 24 and 28 and carry them forwardly with it until it abuts the flange 17. During this period the cutting edge 20 will pass along the ledger blade to perform the cutting operation on the filling ends, and the bell crank lever will be rotated in a clockwise direction to its original position.

It is apparent that during normal operation both filling ends F-1 and F-2 will engage the lever 28 but under some conditions either one of the filling ends may become broken. In such a case, the remaining filling end will engage the lever 28 and will condition the parts of the thread cutter for operation by the forwardly moving lay. Thus, it is to be understood that either one or both of the filling ends will operate the lever 28.

When the lay contacts the flange 17 it will move the temple structure forwardly as a unit and will generate no further relative motion among the parts. However the force of the lay is applied to the parts very rapidly and the inertia of the elements will cause them to continue to move a slight distance beyond the point where actual contact carries them. As a result of this the cutter blade will finally come to rest with the heel portion 24 forwardly of the longitudinal position of the flange 17. Therefore, on subsequent beats of the lay, if the cutter blade is in this forward position, the lay will not contact the heel and the cutter blade will remain stationary relative to the support 16 and the ledger blade 21.

As was noted previously, the cutter blade receives its rearward motion from the bell crank lever 27 by the action of the spring 26 through the interengaging pin 29 and flange 30. This invention provides a means for retaining the bell crank lever in its forward position where it will be unable to actuate the cutter blade unless it is

released therefrom by the pressure of filling ends to be cut.

The bell crank lever has a second arm 37 extending at approximately a right angle to the first arm and disposed along the side face 38 of the support 16. On the same side of the support there is pivotally mounted a second lever 39. The lever 39 may, for convenience, be mounted on the adjusting screw 23. A collar 40 having a nut 41 formed in the end thereof may be screw threaded on the adjusting screw 23 to provide a bearing for the lever and to afford a means for locking the adjusting screw in position.

The second lever 39 has an arm 42 extending downwardly across the arm 37 of the bell crank lever. On the side of the arm 42 facing the support 16 is formed a projection 43 in a position to engage a notch 44 near the end of the arm 37. The dimensions of the parts are such that the projection 43 will seat itself in the notch 44 when the lever 39 is in a vertical position and the bell crank lever has been carried too near its most forwardly position by the action of the lay.

The rearmost vertical edge of the lever 39 lies approximately in the same plane as the rearmost face 45 of the support 16, and in this position it will be contacted by either one or both of the filling ends stretched between the selvage S and the thread holder 10. The adjacent corner of the support 16 is relieved, as at 46, throughout a portion co-extensive with the probable limits of contact of the filling ends and the lever.

The lever 39 is freely revoluble on the collar 40, and under the action of gravity alone will assume substantially a vertical position. A counterbalance 46 may be provided to afford a means for controlling the action of the lever.

Normally, the arm 37 will be held tightly against the projection 43 by the spring 26. When the bell crank lever is so held the arm 28 thereof will be in a position slightly rearwardly of the flange 17. Therefore, when the lay beats up, it will first contact the arm 28 and move it forwardly until the lay abuts the flange 17. As a result, the bell crank lever will be rotated through a small angle in a clockwise direction, enough to relieve the pressure on the projection 43 and free the lever 39.

Now if filling ends are pressing against the arm 42, the lever 39 will be rotated in a clockwise direction and the projection 43 will be unseated from the notch 44. Under these circumstances, when the lay next reciprocates rearwardly to disengage from the arm 28 and the heel 24, the spring 26 will rotate the bell crank lever 27 in a counterclockwise direction causing the nose of the cutter blade to be projected beyond the rearmost face of the support 16 and over the filling ends, which will now reside in the space between the cutting edge 20 and the ledger blade. Hence, when the lay comes forward on the next beat, the filling ends will be severed and drop away from the thread cutter.

When the lever 39 is forced from the vertical position by the action of the filling ends, the projection 43 will contact the edge 47 of the lever arm 37 and ride along it as the lever 27 is rotated in a counter clockwise direction. The arm 27 is bifurcated, as at 48, to receive the lever 39, thereby permitting the bell crank lever to have sufficient throw in this direction to place the cutter blade in an operative position. The action of the lever is limited by the arm 37 striking the collar 40.

A guide member 49 for the bell crank lever may be secured to the temple assembly, using the bolt 50 ordinarily employed to hold the temple top in place.

5 After the filling ends are cut and drop away from contact with the lever 39, it will again assume a vertical position, and the projection 43 will engage the notch 44 to hold the bell crank lever inoperative against the spring 31.

10 The complete cycle of the cutting operation, from the time the bell crank lever is released to the time it is again locked in inoperative position, occurs during two reciprocations of the lay, that is, from a forward position to a rearward position, and forwardly again. Hence it will be seen that the action normally is very rapid. However if the device fails to cut the filling ends when first set in motion, it will continue to operate until the filling ends are cut.

15 The flange 30 on the heel of the cutter blade is formed so that there will be a slight clearance between it and the pin 29 when the bell crank lever is locked in the forward position. Therefore the movement of the lever, when in this position, produced by the action of the lay, will be unable to cause the blade to be moved. As previously explained the heel 24 of the blade also will be in a position forwardly of the flange 17, and hence will not contact the lay. Furthermore the blade will be restrained from free movement by the binding action of the bearing plate 22 and the ledger blade 21. Thus it follows that when the bell crank lever is locked in the forwardly position, the cutter blade will remain stationary. The cutter blade will be in operation only a small part of the time the loom is functioning, and most of the wearing action ordinarily imposed on the cutting edges will thereby be eliminated.

20 30 Having thus described a preferred embodiment of my invention, I claim:

1. In a filling end cutter device for a filling replenishing loom, a temple supporting member located close to the selvage of the cloth, a temple thread cutter blade mounted therein for movement from an inoperative to an operative position, a spring actuated lever mounted on said supporting member and engaging said cutter blade for moving it to an operative position, and means 45 normally holding the said lever inactive with the cutter blade in an inoperative position, said means being constructed and arranged to be actuated by an incoming filling end and an outgoing filling end to release said lever from the inactive position.

2. In a filling end cutter device for a filling replenishing loom, a temple supporting member located close to the selvage of the cloth, a temple thread cutter blade mounted therein for movement from an inoperative to an operative position, a spring actuated lever pivotally mounted on said supporting member and engaging said cutter blade for moving it to an operative position, and means mounted on said supporting member and positioned to engage said lever normally to hold said lever inactive with the cutter blade in an inoperative position, said means being constructed and arranged to be actuated by an incoming filling end and an outgoing filling end to release said lever from the inactive position.

60 65 70 75 2. In a filling end cutter device for a filling replenishing loom, a temple supporting member located close to the selvage of the cloth, a temple thread cutter blade mounted therein for movement from an inoperative to an operative position, a spring actuated lever pivotally mounted on said supporting member and engaging said cutter blade for moving it to an operative position, and means mounted on said supporting member and positioned to engage said lever normally to hold said lever inactive with the cutter blade in an inoperative position, said means being constructed and arranged to be actuated by an incoming filling end and an outgoing filling end to release said lever from the inactive position, whereby said lever will place the cutter blade in an operative position.

3. In a selvage trimming device for a filling replenishing loom having a lay reciprocating between a forwardly and a rearwardly position, a

supporting member having a cutter blade slidably mounted therein for movement forwardly and rearwardly of the loom, a spring actuated lever positioned to engage said cutter blade for imparting motion thereto in a rearward direction, said cutter blade being moved in a forward direction by engagement with the lay, and a locking means for holding said lever in an inactive position where it will be ineffective to move said blade, said locking means being constructed and arranged to be actuated by an incoming filling end and an outgoing filling end to release said lever to move said blade into a position where it will be operable to cut said filling ends, said locking means functioning to lock said lever in an inactive position after the said filling ends are cut.

4. In a selvage trimming device for a filling replenishing loom having a lay reciprocating between a forward and a rearward position, a supporting member having a cutter blade mounted therein for movement from an inoperative to an operative position, a lever pivotally mounted on said supporting member and having a part detachably engaging said cutter blade, a spring for actuating said lever for moving said cutter blade to an operative position, said lever and said blade having parts engageable by the lay to move said cutter blade to an inoperative position, and locking means operatively mounted on said supporting member to hold said lever out of engagement with said cutter blade when the cutter blade is in an inoperative position, said locking means being constructed and arranged to be actuated by an incoming filling end and an outgoing filling end to release said lever to engage said cutter blade and place it in an operative position to cut said filling ends, said locking means functioning to hold said lever in an inoperative position after the filling ends are cut.

5. In an intermittent temple thread cutter for a loom having a lay reciprocating between a forward and a rearward position, a supporting member, a cutter blade mounted therein for movement from a forward to a rearward operative position, a bell crank lever pivotally mounted on said supporting member for rotation from a forward to a rearward position and having a portion thereof abutting said cutter blade, a spring connected to said bell crank lever for moving said lever and said cutter blade in a rearward direction, said lever and said cutter blade having parts engageable by the lay for imparting movement thereto in a forward direction, and locking means mounted on said supporting member normally to lock said bell crank lever in a forward position, said locking means being constructed and arranged to be actuated by an incoming filling end and an outgoing filling end to release said bell crank lever from the locked position to thereby move the cutter blade rearwardly into an operative position to cut the said filling ends.

6. In an intermittent temple thread cutter, a supporting member having a cutter blade operatively mounted therein, an actuating means for

10 the cutter blade comprising a bell crank lever rotatably mounted on said supporting member and having one lever portion extending adjacent a portion of said blade and another lever portion extending horizontally along the side of the supporting member, the first said lever portion having a projection formed thereon extending toward and detachably engaging said cutter blade, a spring for biasing said bell crank lever for rotation in a direction to cause the said cutter blade to be projected rearwardly to an operative position through the interaction of the said engaging parts, a second lever pivoted to said supporting member adjacent the rearward end of said bell crank lever and positioned to engage and hold said bell crank lever against the rotative action of the spring to cause said cutting blade to remain in an inoperative position, said second lever being constructed and arranged to be actuated by an incoming filling end and an outgoing filling end to release said bell crank lever to place said cutter blade in an operative position to cut said filling ends, said second lever functioning to re-engage the bell crank lever after the filling ends are cut.

20 7. In a selvage trimming device for a filling replenishing loom having a lay reciprocating between a forward and a rearward position, a supporting member, a cutter blade slidably mounted therein for movement from a forward to a rearward position, a bell crank lever pivotally mounted on one side of said supporting member for rotation from a forward to a rearward position, said lever and said blade having depending portions 30 thereon extending into the path of the lay, said depending portion of said lever having a pin projecting therefrom and detachably engaging said depending portion of said blade, a spring connected to said lever for causing rotation thereof in a direction to impart rearward motion to said blade, said lever and said blade being returned to a forward position by the action of the lay on said depending portions thereof, said bell crank lever having another portion extending in a rearward direction, a second lever pivotally mounted on the side of the supporting member and adjacent the rearward end of the said other portion of the bell crank lever, said second lever having a projecting part positioned to engage a notch in the rearwardly extending portion of the bell crank lever when the said lever is rotated by the lay to the most forward position, the said second lever functioning as a locking means to hold the said bell crank lever in its most forward position to thereby prevent it from moving the cutting blade rearwardly, said second lever being constructed and arranged to be actuated by an incoming filling end and an outgoing filling end to release said bell crank lever to place said cutting blade rearwardly in an operative position to cut said filling ends, said second lever functioning to lock said bell crank lever in a forward position when said filling ends are cut.

25 35 40 45 50 55 60 JAMES E. REPASS.
